NOVELTY

Benjamin Fried, Brooklyn, N. Y.

Application October 9, 1937, Serial No. 168,117

4 Claims. (Cl. 40—67)

This invention relates to a novelty and more particularly to an advertising device adapted to attract the attention of the reader of a piece of advertising matter and to direct his gaze to a particular portion thereof.

An important object of this invention is the provision of improved means for causing a figure to vibrate.

Another object of this invention is to provide a novel attention-attracting device for advertising matter, such as advertising folders.

Still another object of this invention is to provide novel devices for attachment to educational cards, books and the like.

Other objects of this invention, together with certain details of construction and combinations of parts, will be apparent from the following detailed description and pointed out in the appended claims.

20 In the accompanying drawing:

Figure 1 is a detail view of a spring device;

Figure 2 is a plan view showing the spring device as attached to a figure representing an arm and hand;

25 Figure 3 is a view showing the spring device and attached figure as mounted and positioned in a closed folder;

Figure 4 is a view showing the position of the spring device and attached figure when folder is open;

Figure 5 is a view showing the position of the figure (in dotted lines) when folder is closed;

Figure 6 is a view showing position of figure when folder is open; and

30 Figure 7 is a side elevational view of a modified form of spring device.

Similar characters of reference indicate similar parts throughout the several views of the drawing.

40 Referring to the drawing, the spring device, generally indicated by reference numeral 9, comprises a hair-spring 11 of any suitable material but preferably of metal. On one extremity of said

45 hair-spring is suitably attached a flat member 12 which is adapted to be affixed to a card, book or, as shown, to a folder 13. At or near the other extremity of the hair-spring is mounted a weight

45 14. This weight is also preferably flat and is adapted to have mounted thereon a figure 15 which, in the modification shown is that of an arm and hand.

50 In Figures 3 and 4, the spring device 9 to which the figure 15 is attached is shown mounted on page A in the folder 13. In closing the folder

page B of the same forces the figure 15 to the right placing the spring 11 under tension so that when the folder is again opened, as by one looking for the contents on the inside thereof, the tension on the spring 11 is released causing the 5 spring 11 and figure 15 to vibrate or oscillate thereby attracting attention thereto.

In Figures 5 and 6, the figure 15 representing an arm and hand 15 and the spring to which it is attached are forced to the right so that when 10 the folder is opened the tension on the spring is released whereupon the figure 15 oscillates in the plane of the open folder. As the folder 13 is held in the hand, the quiver or shaking of the hand, such as is caused by the pulse beat, causes 15 the figure 15 to continue its oscillation since the figure is mounted on such a thin spring. This is of advantage for it continues to attract the eye to the portion of the folder to which the hand is pointing.

20 In Figure 7, there is shown a modification of my invention. In this modification the figure 15 is mounted on one end of a coiled hair-spring 16, the other end of which is affixed to a folder, etc.

25 Many other desirable effects may be produced in accordance with my invention. For example, the effect of a person or of a couple dancing may be obtained by mounting the proper figures on one or more spring devices. Such effects may be used on display posters as well as advertising matter which is normally mailed. Furthermore, figures of animals may be mounted on pages of books, particularly those intended for children, in order to give to these animal figures an animated effect. My invention may also be placed in lids of packages of cereals and other packaged foods. When the lids are opened, the figure mounted thereon will be caused to oscillate.

30 It is to be understood that the foregoing detailed description is given merely by way of illustration and that many variations may be made therein without departing from the spirit of my invention.

35 Having described my invention, what I claim as new and desire to secure by Letters Patent of the United States is:

40 1. A folder comprising two pages, one of said pages having a representation of part of a figure thereon, a spring fixed to one of said pages and a member mounted on said spring, the construction and arrangement being such that when the folder is opened, the said member is caused to move to such position as to form a complete representation of the figure.

2. A folder comprising two pages, one of said pages having a representation of part of a figure thereon, a spring fixed to one of said pages and a member adapted to oscillate mounted on said spring, the construction and arrangement being such that when the folder is opened, the said member is caused to move to such position as to form a complete representation of the figure and to oscillate in said position.
- 10 3. A folder comprising two pages, one of said pages having a representation of a part of a figure thereon, a spring fixed at one end to one of said pages, a weight mounted on said spring and a member mounted on said spring, the construction and arrangement being such that when the folder is opened, the said member is caused to move to such position as to form a complete representation of the figure and to oscillate in said position.
- 15

folder is opened, the said member is caused to move to such position as to form a complete representation of the figure.

4. A folder comprising two pages, one of said pages having a representation of a part of a figure thereon, a spring fixed at one end to one of said pages, a weight mounted at the free end of said spring adapted to enhance oscillation of said spring and a member mounted on said spring, the construction and arrangement being such that when the folder is opened, the said member is caused to move to such position as to form a complete representation of the figure and to oscillate in said position.

BENJAMIN FRIED. 15
